UNITED STATES PATENT OFFICE.

HENRY K. EILERS, OF PLAINFIELD, NEW JERSEY, AND MARQUIS H. LOCKWOOD, OF NEW YORK, N. Y., ASSIGNEES TO PYRAMID IRON PRODUCTS CORPORATION, A CORPORATION OF NEW YORK.

GRATE BAR.

Application filed October 18, 1923. Serial No. 669,248.

Our invention relates more particularly to grate bars for boilers and furnaces to adapt them for the more efficient use of fine coal, either anthracite or bituminous. Our improvement is more specifically an improvement upon the grate bar shown and described in Patent No. 1,140,158 of May 18, 1915, to C. W. Hopes, and is intended to more efficiently operate in connection with the use of fine or low grade coal. In the Hopes patent, it will be noted that the air passages under the caps extend continuously under all of the caps in each direction, and, therefore, the currents of air coming under the caps encounters similar air currents from the adjoining caps and the air mushrooms up between the caps. The Hopes arrangement lends itself to irregular distribution of the air and, therefore, uneven burning of the coal. This will occur when an air passage between caps becomes slightly blocked by a greater amount of coal, or for other reason, and offers more resistance to the passage of air; the air will then be diverted through a passage offering less resistance and in this way produce uneven burning.

The object, therefore, of our improvement is to provide a single air passage under each cap, so arranged that it is completely independent of the air passage of any other cap and compels a uniform supply of air over the entire grate, and prevents interference or irregular distribution of the air currents.

In grates of this character, it is found in practice that, due to the uneven combustion of the fuel, the caps may be burned off or weakened to such an extent that it is desirable to replace them and, therefore, a further object of our improvement is to provide a grate bar of this character, with caps removably attached thereto, so that at any time the caps become burned to such an extent that a renewal thereof is desired, it will not be necessary to renew the entire grate bar, but the old caps can be replaced with new caps, each individually attached by suitable means to the grate bar.

It will be understood also that our improved grate bar construction may be readily adapted for use in connection with either hand fired boilers or furnaces, or with boilers fitted with mechanical stokers or traveling grates of the usual or any preferred construction.

For the purpose of illustration, we have shown in the accompanying drawings, the preferred form of our improved grate bar, together with modifications, but obviously, other modifications involving the same principle may be employed. Fig. 1 shows a plan view of a grate bar embodying our improvement; Fig. 2 is a longitudinal vertical section of our improved grate bar, the section being taken on the line 2-2 of Fig. 1; Fig. 3 is a transverse vertical section of the grate bar on the line 3-3 of Fig. 1; Fig. 4 is a fragmentary enlarged view of a portion of the grate bar in section under the caps, which are removed; Fig. 5 is a plan view of a slight modification of our improved grate bar, in which the caps are shown in staggered relation; Fig. 6 is a vertical section of a portion of the grate bar of Fig. 5, on the line 6-6; Fig. 7 represents a transverse vertical section of the grate bar shown in Fig. 5 on the line 7-7; Fig. 8 is a fragmentary vertical section through a modified grate bar, arranged as in Figs. 1 to 4, except that the caps covering the air passages are removably attached to the body portion of the bar; Fig. 9 is a fragmentary horizontal section on the line 9-9 of Fig. 8, and Fig. 10 is a slight modification in the removable cap construction.

Referring to the drawings, it will be seen that our improved grate bar comprises a body portion 1, provided with a plurality of perforations 2, forming vertical air passages therethrough. The vertical air passages 2 may be of any desired size and arranged in any suitable manner, according to the requirements of any particular grate construction but are preferably arranged in longitudinal and transverse rows as indicated in Fig. 1 of the drawings. Each of the perforations or vertical air passages 2 is covered by a cap 3 which forms the upper wall of a single transverse air passage 4, communicating with the vertical air passage 2, between walls 4^a; and extends horizontally substantially at right angles thereto.

The grate bars may be cast with the caps integral with the body portion as shown in Figs. 1 to 3, in which case the caps are separated and defined by V-grooves 5 and 6, extending longitudinally and transversely of the grate bar, as more particularly seen in Fig. 4 of the drawings. The outlet ends 7

of the horizontal air passages 4, under the caps 3 open into one or the other of the V-grooves 5 and 6 and therefore, discharge air into the V-groove, against the inclined side wall thereof; the latter forming the wall 4^a of the transverse air passage of the adjacent cap. In other words, in this form, each cap covers a single transverse air passage in communication with a vertical air passage 16 and the transverse air passages of adjacent caps are at right angles to each other. By this arrangement, it will be seen that the discharge of air from the openings 7 of the transverse passage of each cap, is entirely 22 independent of the air discharge from surrounding adjacent caps.

In order to facilitate the discharge of air from the vertical air passages 2, the lower wall 8 of the transverse air passage 4, on each side of the perforations is preferably beveled, or inclined, as indicated in Figs. 2 and 3 of the drawings. By making the grooves 5 and 6 between the caps 3 V-shaped, as indicated, it will be seen that the sloping 25 side walls of the respective caps 3 will act as deflectors in cooperation with the inclined lower wall 8, and facilitate the discharge of air from the openings 7 of the transverse air passages. Obviously, the shape of the 30 intersecting grooves 5 and 6, which delimit the caps 4 may be varied as desired, and may be of any other suitable outline. The relative arrangement of the transverse passages under the caps in this form, showing 35 the passages at right angles to each other in adjacent caps is more particularly brought out in Fig. 4, where the caps are shown removed.

In Figs. 5, 6 and 7, we have shown a 40 slight modification in which the construction of the air passages under the respective caps is substantially the same as shown in Figs. 1 to 4, but in this form, the caps over the air passages are arranged in staggered form, 45 and the horizontal or transverse air passages, under the respective caps are in parallel relation. Obviously, however, the staggered arrangement of the caps may be followed and yet have the transverse air passages alternately at right angles, after the 50 manner described for the form shown in Figs. 1 to 4. In Figs. 5 to 7, the corresponding parts are given the same reference numerals as in the previously described construction, but in this case, the transverse V-grooves which delimit the side walls of the 55 caps do not extend continuously, but only for the length of each cap, as indicated at 6^a. The longitudinal grooves 5, however, 60 correspond with the longitudinal grooves of the form shown in Fig. 1.

It is found in practice that under some 65 conditions, the caps 3 covering the individual air passages, occasionally become burned or broken off and naturally this in-

terferes with the uniform distribution and consumption of coal. It is expensive and not always desirable to remove the entire grate bar to repair damages, and for this reason, it is preferred to provide means for 70 removably attaching the caps covering the air passages, so that individual caps may be replaced if they should become broken or burned out. Obviously, any suitable attaching means may be employed and if desired, 75 the entire grate may be made up of caps removably attached thereto. A grate bar of this character, substantially similar to the one shown in Figs. 1 to 4, is indicated by the construction shown in Figs. 8 and 9 of 80 the drawings. In this removable-cap construction, the caps 3^a are provided with lugs 9, which, in the present instance, are indicated as a malleable strip of iron, cast with the cap 3^a. The attaching lugs 9 preferably 85 extend downward through the vertical perforations or air passages 2, and the lower ends 10 thereof are bent outward, as indicated in Fig. 8 to secure the caps to the body portion. Preferably, when this construction 90 is adopted, the air passages 2 are provided with recesses 11, for accommodating the lugs 9, which depend from the under side of the respective caps. To position the caps 3^a between the walls 4^a of the transverse air 95 passages 4, and prevent them turning, they are preferably provided with beads or ledges 12. The ledges or beads 12 also prevent lateral displacement of the caps in one direction, while the engagement of the lugs 9 100 in the recesses 11 will prevent displacement in the other direction.

In the forms shown in Figs. 1, 5 and 8, of the drawings, we have shown the caps 3 and 105 3^a as a truncated pyramid, but obviously, the shape of the caps may be varied and we have shown a slight modification in Fig. 10. In this form of cap, the upper surface 13 is curved and may be spherical or cylindrical. In this form, also, the lugs 14 for securing 110 the caps to the body portion of the grate bar are represented as similar to wire nails, with the heads cast into the caps, so that the lugs of fastening devices become integral therewith.

While we have shown our improved grate bar in the preferred form, with slight modifications, it will be obvious that we do not wish to be limited to the specific details of construction, nor to any particular size, 115 shape or arrangement of the air passages, for various modifications therein may be made without departing from the spirit and scope of the invention.

We claim:—

1. A grate bar comprising a body portion, provided with a plurality of symmetrically arranged perforations for the passage of air, a corresponding plurality of caps covering said perforations, each cap forming with the 120

body portion of a single transverse air passage, at right angles to said perforations, the caps being close together and having their edges beveled so that with the bevel of adjacent caps V-grooves are formed about each cap, the arrangement of the transverse air passage being such that air passing out of said passages will impinge upon the beveled side walls of air passages of adjacent caps.

2. A grate bar comprising a body portion, provided with a plurality of vertical air passages, caps covering said vertical air passages, said caps being arranged symmetrically close together and having beveled edges forming longitudinal and transverse grooves

therebetween, a single air passage extending horizontally under each cap and in communication with the respective vertical air passages, the arrangement of said horizontal air passages being such that air passing out of said passages enters said grooves and impinges against the closed walls of the horizontal air passages of adjacent caps. 20

3. The grate bar as claimed in claim 2, in which the single horizontal air passages of the respective caps are at right angles to the single horizontal air passages of adjacent caps in each direction. 25
